UNITED STATES PATENT OFFICE.

ELI J. BUSHEY, OF NEW YORK, N. Y.

GAS-MOISTENING APPARATUS.

1,275,379.

Specification of Letters Patent. Patented Aug. 13, 1918.

Application filed August 19, 1914. Serial No. 857,520.

To all whom it may concern:

Be it known that I, ELI J. BUSHEY, a citizen of the United States, and a resident of New York, county and State of New York, 5 have invented certain new and useful Improvements in Gas-Moistening Apparatus, of which the following is a full, clear, and exact description.

This invention relates more particularly 10 to the method of and apparatus for saving gas and for cleaning the cylinders of gasoline engines of carbon.

One of the principal objects of the invention is to provide a simple attachment which 15 may be applied to gasoline engines of automobiles or other vehicles without changing the construction of the same and by which and the method resulting therefrom, steam or vapor and air may be mixed with the gas 20 or explosive mixture between the carbureter and the cylinders of the engine, thereby economizing in the use of gasoline and at the same time increasing the speed and causing the carbon deposit in the engine cylinders 25 to be automatically removed by the steam.

Another object of the invention is to provide simple and efficient means and method whereby the cylinders of gasoline engines 30 may be specially treated for the removal of carbon or other foreign deposit.

A further object of the invention is to provide an attachment or apparatus which is inexpensive to manufacture and which may 35 be readily made and assembled and applied to various kinds of engines as ordinarily constructed.

With these and other objects in view, the invention will be hereinafter more particularly described, with reference to the accompanying drawings, which form a part of this specification, and will then be pointed out in the claim at the end of the description.

In the drawings, Figure 1 is a side elevation of one form of automobile engine with the invention applied thereto.

Fig. 2 is a vertical section of a part of the apparatus.

Fig. 3 is a section taken on the line III— 50 III of Fig. 2.

The engine 10 has one or more cylinders 11 and is provided with the usual carbureter 12 having a throttle which may be operated by a crank 13 and by a rod 14. Above the 55 carbureter or gas supplying means is an intake or gas conduit 15 which is connected

to the cylinders, and leading from the cylinders is an exhaust pipe 16. The parts thus described may be of the usual or of any preferred construction.

A tank 17 may be suitably attached to or supported on the dash-board 18 of the vehicle. This tank may be cylindrical in form or otherwise made and is provided with a closed bottom 19 and a removable cap or 60 cover 20. A pipe 21 extends vertically through the tank and this pipe 21 is open at the top above the cap 20 and at the lower end is provided with a union or coupling 22 so as to form a continuation of a pipe 23. 65 The pipe 23 may be separate from or integral with the pipe 21 and said pipe 23 is provided with a plurality of convolutions 24 about the exhaust pipe 16, by which the liquid or other fluid passing through the 70 pipe will be heated by the exhaust from the engines, the exhaust pipe serving as a heating drum. The pipe 23 at its lower end communicates with the intake 15 above the carbureter 12 and in said pipe 23 is a valve 75 25. This valve 25 has an operating arm 26 which may be connected by a link 27 or otherwise to the throttle rod 14 and in such a way that the throttle is opened to start the engine and have the same running before the valve 26 is open to permit the fluid from the pipe 23 to enter the intake 15 and mix with the gas passing through the carbureter.

The pipe 21 in the tank 17 is provided at 80 the lower portion thereof with a plurality of openings 28 and these openings are covered by a felt washer or gasket 29 or otherwise so that water, as 30, within the tank 17 may seep through the felt or other covering through the openings and pass with the air from the atmosphere through the pipe 21 to the pipe 23 around the exhaust pipe and there heated so as to heat the air and convert the water or vapor into steam so 85 that the latter may be commingled with the gas passing from the carbureter to the engine in an amount according to the opening of the valve 26 and according to the position or the amount of opening of the throttle.

It will be evident that the air and vaporized water being supplied to the engine in addition to the usual supply of explosive mixture will materially reduce the quantity 90 necessary to run the engine, thereby economizing in the use of gasoline. The steam

also serves further to clean the engine cylinders of carbon so that a saving is accomplished in this way. The invention also serves to add to the speed as it has been demonstrated in practice that when the engine is running and the valve 26 is open, the speed of the engine is thereby materially increased.

When it is desired to thoroughly clean the engine cylinders if they become dirty through deposits of carbon, etc., and when first attaching the invention to an engine already in use, I employ a scavenging attachment. This is shown in Fig. 2 in the form of a pipe 31 leading from the bottom of the tank 17 and communicating with the pipe 21 beneath the tank. In this pipe 31 is a valve 32 which may be opened by hand and which will permit a larger supply of water to pass through the pipe 21 than would naturally seep through the packing 29. In using the scavenging attachment, the engine is usually run at a high speed before the valve 32 is opened. By this method and apparatus an effectual cleaning of the cylinder or cylinders is secured.

Having thus described my invention, I

claim as new and desire to secure by Letters Patent:—

A gas moistening apparatus comprising a gas supply conduit, a heating drum, a water tank, a pipe connected at its outlet end with said gas conduit and passing upwardly through said water tank and having an open intake end located above said tank, said pipe being provided with a series of perforations communicating with the interior of said water tank and being coiled about said heating drum at a point between said perforations and the outlet end of the pipe, a sleeve of porous material fitting about said pipe within the tank and extending over the perforations in the pipe, means for creating a suction through said pipe, and a valve in said pipe for controlling the passage of moistened air therethrough to the gas supply conduit.

This specification signed and witnessed this 14th day of August, A. D. 1914.

ELI J. BUSHEY.
